LIFEBOAT LAUNCHING APPARATUS

John L. Hyland, New York, N. Y.

Application March 12, 1931, Serial No. 522,028

13 Claims.

(Cl. 9—22)

This invention relates to an improvement in life boat launching apparatus of the type set forth in my former application Serial No. 453,393, filed May 17, 1930.

5 The object of the invention is to improve the manner of launching life boats and to facilitate the actuation of the launching mechanism so that the life boats may be launched from either side of a ship regardless of the listing thereof and 10 may even be launched from the high side of a listed ship. It is also possible with this invention to be able to launch a life boat while it is underway, which is permitted by the quickness with which the life boat may be launched.

15 In the accompanying drawings:

Fig. 1 is a side elevation of the apparatus applied to the deck of a ship and showing in dotted lines the positions of the parts when the life boat is partially launched;

20 Fig. 2 is a top plan view of the same;

Fig. 3 is a side elevation taken at right angles to the position shown in Fig. 1;

25 Fig. 4 is a transverse vertical sectional view through a portion of the apparatus and showing the lowering mechanism;

Fig. 5 is a detail sectional view showing the manner of connecting the lines to the life boat; and

Fig. 6 is a detail top plan view of the same.

30 The deck of the ship is designated generally by the numeral 1 and has an upstanding wall 2 supported thereon, which may be the wall of a cabin or the like and which will serve as a suitable rigid support.

35 The life boat is designated by the numeral 3 and is adapted to be supported in an upright position above and upon the deck 1 when stored, so that it may be pushed over a side of the ship and lowered to the surface of the water. A cover 4 is arranged over the life boat 3 to cover the same when in stored position on the deck 1.

40 For supporting the life boat 3, davits 5 are provided, which are hinged as at 6 to brackets 7 extending upright on the deck 1. A plurality of the davits 5 are shown suitably spaced apart, as illustrated particularly in Figs. 3 and 4, to support the life boat in stored position. To receive the life boat, each of the davits 5 has a projecting lip 8 on the opposite side of the pivot 6 from the major portion of the davit, and which projecting lips receive the life boat as shown in Fig. 1.

45 Each of the davits 5 is approximately L shaped, as shown in Fig. 1, and has the arm of the L extending upwardly, as is designated by the numeral 9. A downwardly extending heel 10 is pro-

vided for supporting the angle of each L shaped davit 5.

The upper ends of the arms 9 of the davits are pivoted by a shaft 11 to a frame 12. This frame 12 carries guard rails 13, which extend transversely across behind the life boat 3 and move outward therewith as a protection for the passengers, and this frame has forwardly extending arms 13⁵ for supporting the life boat cover 4.

5 As a means of swinging the davits 5 on their pivots 6, a sleeve 14 is secured to the frame 12 and is internally threaded to receive an externally threaded screw 15, which is threaded therethrough and has its back end received within and secured to the universal or pivoted joint 16, as 10 shown in Fig. 1, which will allow rocking of the screw 15. A gear 17 is fixed to the screw 15 to turn the same, and this gear 17 is driven by means of a pinion 18 and a handle 19 connected therewith, so as to turn the screw 15 to feed the 20 frame 12 outward, and which action causes a pushing of the life boat 3 off of the side of the deck.

25 As a means of supporting the life boat, the arms 13 have guide rods 22 carried thereby, over which cables 21 extend, and which guide rods 22, as shown in Fig. 2, are inclined toward each other in approximately V shape. The ends of the cables 21 are wound around a shaft 23 and have their extreme ends fixed to said shaft. This shaft 23 is 30 turned by gears 24 fixed to the opposite end portions thereof, which mesh with idle gears 25 carried by the frame 12, and the latter of which mesh with idle pinions 26 mounted on a main drive shaft 27 which also forms one of the guard 35 rails. As shown in Fig. 4, this shaft 27 has a bevel gear 28 fixed thereto and is driven by a bevel pinion 29 and a hand-wheel 30. The cables 21 serve to support the life boat 3 and to lower or 40 raise the same.

45 The lower ends of the lines 21 have loops 31 connected therewith as shown in Figs. 5 and 6, which loops 31 are adapted to receive pins 32, which may be formed integral with or carried by an enlarged portion 33 of a shaft 34, journaled in the life boat 3. The enlarged portion 33 is notched out to form the pin 32, as shown in Figs. 5 and 6, and this pin 32 is slightly off-center, as shown in Fig. 5 which disposes the loop of the rope approximately at the center of the 50 shaft. The enlarged portion 33 is disposed within a casing 35, so that when the pin 32 receives the loop 31 and is turned to the position shown in Figs. 5 and 6, the casing prevents the release of the loop 31 from the pin and holds the lines 55

21 to the shaft 34. The shaft is provided with an arm 36 for turning the same and which arm may be received in an opening 37 formed within a resilient latch 38, extending upwardly from 5 the bottom of the life boat 3 as a means of holding the shaft 34 in a fixed position and to secure the lines 21 thereto.

When the life boat is in stored position on the deck of a ship, it is desirable to secure the same 10 in a rigid position, and for this purpose lines 39 and 40 each have one end fixed to the deck 1. The line 39 has a loop 41 therein, through which the line 40 extends. The line 40 has a pin 42 secured thereto and extends into an orifice in a 15 projecting end portion of the screw 15. In this way, when the screw has been turned to draw the life boat into a stored position, the pin 42 is inserted into the end thereof to hold the cover 4 and the frame connected therewith securely 20 down to the deck of the ship. Any further turning movement of the screw 15 will tighten the lines 39 and 40 and increase this holding action.

As a further means of holding the mechanism securely down on the deck, chock lines 43 are 25 connected with the life boat and extend upwardly to the frame 12.

To hold the cables 21 close to the side of the ship when launching the life boat, links 44 receive the lines 21 at one end, and at the opposite 30 site end receive guide cables 45, which extend upwardly beside and fixed to the frame 12, as shown particularly in Fig. 1. This serves to effectively hold the life boat in a position close to the side of the ship until the passengers have 35 been loaded therein.

In the operation of the apparatus, the life boat 3 is normally in the position shown in full lines in Fig. 1, where it is stored on the deck of a ship and is supported by the projections 8 of the 40 davits 5. To launch the life boat, the handle 19 is first turned in order to rotate the screw 15 and feed the sleeve 14 and frame 12 outward. The first turn of the screw 15 moves the pin 42 to an upright position, where it drops out of its hole 45 by gravity in order to release the lines 39 and 40. Further rotation of the screw 15 causes the frame 12 to be moved outward to the dotted line position in Fig. 1, which swings the davits 5 upward about their pivots 6, until the frame 12 50 rests on the edge of the deck 1.

The hand-wheel 30 is then turned to rotate the shaft 23 through the bevel gears 28 and 29, the shaft 27, the pinions 26, and the gears 24 and 25, which permits the cables 21 to unwind from 55 the shaft 23 and lower the life boat. As the life boat is lowered from its uppermost position, the links 44 follow downward with it as far as permitted by the guide cables 45 to hold the life boat close to the deck of the ship.

60 As the life boat reaches the surface of the water, it is desired to cast off the cables 21, and to do this it is only necessary to release the arm 36 from its resilient catch 38 and turn the shaft 34 to turn the pin 31 in an upright direction, 65 which permits the loops 32 to be released therefrom to cast off the life boat from these cables.

The reverse of this operation serves to connect the life boat and raise the same to a stored position on the deck of the ship.

70 It is possible with this invention to carry the life boat outside the deck, where it will be just as well protected as when on the deck, and it may be lowered immediately. This leaves the deck clear for the passengers.

75 I claim:

1. In life boat launching apparatus, the combination of a supporting frame, means for supporting a life boat therefrom, one or more approximately L shaped davits pivotally supporting the frame, brackets pivotally connected with one arm of each of the L-shaped davits for supporting the same, and a heel connected with each of the davits at the angle thereof for supporting the main portion of the davit when in retracted position. 10

2. In life boat launching apparatus, the combination of a supporting frame, a shaft carried thereby, one or more approximately L shaped davits having one arm thereof connected with the shaft for pivotally securing the same to the frame and for supporting the frame on the davits, brackets pivotally secured to the other arms of the L shaped davits, and a heel formed on each of the davits at the angle thereof for supporting the same in retracted position. 15

3. In life boat launching apparatus, the combination of a supporting frame, a shaft carried thereby, one or more approximately L shaped davits having one arm thereof connected with the shaft for pivotally securing the same to the frame and for supporting the frame on the davits, brackets pivotally secured to the other arms of the L shaped davits, a heel formed on each of the davits at the angle thereof for supporting the same in retracted position, approximately V shaped guide members carried by the frame, cables extending over said guide members for supporting a life boat from the frame, and gearing controlling the action of the cables. 20

4. In life boat launching apparatus, the combination of a supporting frame, a shaft carried thereby, one or more approximately L shaped davits having one arm thereof connected with the shaft for pivotally securing the same to the frame and for supporting the frame on the davits, 40 brackets pivotally secured to the other arms of the L shaped davits, a heel formed on each of the davits at the angle thereof for supporting the same in retracted position, approximately V shaped guide members carried by the frame, cables extending over said guide members for supporting a life boat from the frame, gearing controlling the action of the cables, an internally threaded sleeve carried by the frame, a screw threaded through said sleeve, means for fixing an 45 end of said screw, and means for turning the screw to cause lateral swinging movement of the sleeve and frame. 50

5. In life boat launching apparatus, the combination of a supporting frame, a shaft carried thereby, one or more approximately L shaped davits having one arm thereof connected with the shaft for pivotally securing the same to the frame and for supporting the frame on the davits, brackets pivotally secured to the other arms of the L shaped davits, a heel formed on each of the davits at the angle thereof for supporting the same in retracted position, an internally threaded sleeve fixed to the frame, a screw threaded through said sleeve, means for fixing an end of 60 said screw, and means for rotating the screw for causing lateral swinging movement of the frame. 65

6. In life boat launching apparatus, the combination of a frame, one or more davits pivotally connected therewith and for supporting the frame, a pivotal support for the davits, means connected with the frame for swinging the same outward on the davits, an approximately V shaped guide, at least two cables extending over the guide at opposite sides of the V shaped por- 75

- tion, a shaft about which said cables are wound, and means connected with the shaft for turning the same to control the movement of the cables.
7. In life boat launching apparatus, the combination of a supporting frame, davits for pivotally supporting said frame, means for causing lateral swinging movement of the frame on the davits, an approximately V shaped guide carried by the frame, cables extending over opposite sides 10 of the V shaped guide for supporting the life boat, a shaft about which said cables are wound, a main drive shaft, gearing connecting the first-mentioned shaft with the main drive shaft, and bevel gearing for driving said main drive shaft.
- 15 8. In life boat launching apparatus, the combination of a frame for supporting the life boat, a shaft mounted in the frame and having an orifice therein, and a cable having the lower end thereof fixed and carrying a pin at the upper end 20 to extend into the orifice in the shaft, to hold the frame and life boat securely in a stored position.
9. In life boat launching apparatus, the combination of a davit for supporting a life boat in stored position, a shaft carried by the davit and 25 having an orifice therein, one or more lines having the lower ends thereof fixed, and a pin connected with the upper ends of the lines and adapted to extend into the orifice for securely holding the life boat in a stored position.
- 30 10. In life boat launching apparatus, the combination of a davit, a frame carried by the davit and having means for supporting a life boat, a cover for the life boat and carried by the frame, a shaft connected with the frame and having an orifice therein, a plurality of lines having the lower ends thereof fixed and having their upper 35 ends connected together, and a pin connected with said upper ends and slidably extending into

the orifice to anchor the life boat in a secure position.

11. In a life boat, the combination of a shaft having a notch formed therein and a pin fixed to a side thereof within the notch and adapted 5 to receive a supporting line, a casing within which said pin is mounted to prevent the release of the line therefrom when turned to a downward position, and means for turning the shaft.

12. In a life boat, the combination of a shaft 10 having a notch formed therein and extending approximately to the center of the shaft, and a pin fixed to the inner side of the notch for receiving a supporting line, said pin extending laterally from a point approximately beside the center of 15 the shaft, and a casing about said notch and pin.

13. In life boat launching apparatus, the combination of fixed supporting structure, movable frame structure, means supporting said movable frame structure on the fixed supporting structure 20 for movement between a retracted position and a forward life boat launching position, means for holding the movable frame structure substantially horizontal during said movement, a rigid life boat cover permanently secured to the movable frame 25 structure in position to overlie the life boat, means carried by the movable frame structure for supporting the life boat beneath the cover and for lowering the life boat away from the cover without removal of the cover, a shaft rotatably associated with the cover and having an orifice therein, one or more lines having the lower ends thereof fixed, and a pin connected with the upper ends of the lines and removably inserted into the orifice 30 for securely holding the life boat in a stored position.

JOHN L. HYLAND.
